UNITED STATES PATENT OFFICE.

WILLIAM M. DOTY, OF JANEVILLE, WISCONSIN.

IMPROVEMENT IN WAGON-JACKS.

Specification forming part of Letters Patent No. **56,192**, dated July 10, 1866.

To all whom it may concern:

Be it known that I, WILLIAM M. DOTY, of Janesville, in the county of Rock and State of Wisconsin, have invented a new and useful Improvement in Wagon-Jacks; and I do hereby declare that the following is a full, clear, and exact description thereof, which will enable others skilled in the art to make and use the same, reference being had to the accompanying drawing, forming a part of this specification.

The wagon-jack embraced in the present invention consists of a standard and an upright bar moving and sliding on one of its sides, to which it is held by one or more clasps, which act also as clamps to hold it at any height to which it may be raised by means of a lever-arm hung and turning upon a fulcrum at its upper end, when applied to the axle of a wagon to lift it sufficiently to raise the wheel hung thereon from the ground, as will be apparent from the following detail description thereof, reference being had to the accompanying plate of drawing, the figure of which represents a perspective view of the wagon-jack.

A in the drawing represents a standard, fixed at its lower end to a suitable bed-piece, B; C, a vertical bar applied to one side, D, of standard A, on which it moves or slides in a vertical direction by a groove, a, and tenon, b; E, a clasp extending loosely around the bar C, and fastened at each end to the sides of the upright standard A by a pin, c, in each

end, on which it turns; F, a lever-arm hung upon a fulcrum, d, in the slot G of the upper end of the bar, by which lever, when the jack is placed under the axle-tree of a wagon for the purpose of lifting its wheel from the ground the axle-tree is raised, the bar C moving upward at the same time, when, removing the hand from the lever, the downward pressure or weight then coming upon the said bar C, necessarily causes its clasp E to tightly bind and clamp it to the standard, as is plain to be seen by an inspection of the drawing, thereby preventing the bar from slipping downward and firmly holding it at such height.

In lieu of only one clasp, E, more may be used; but one I deem sufficient, although I do not intend to limit myself to any particular number of them to be used.

I claim as new and desire to secure by Letters Patent—

The arrangement of the clamp E and standard A, operating in combination with the sliding bar C and lever-arm F, without serrations on the sliding bar C, substantially in the manner and for the purpose represented and described.

The above specification of my invention signed by me this 7th day of February, 1866.

WILLIAM M. DOTY.
